UNITED STATES PATENT OFFICE.

CLEMENT KATCHIR, OF OAKWOOD, ILLINOIS.

PERMUTATION DOOR-KNOB LOCK.

1,124,622.

Specification of Letters Patent.

Patented Jan. 12, 1915.

Application filed September 14, 1914. Serial No. 861,583.

To all whom it may concern:

Be it known that I, CLEMENT KATCHIR, a subject of the Emperor of Austria-Hungary, residing at Oakwood, in the county of Vermilion and State of Illinois, have invented certain new and useful Improvements in Permutation Door-Knob Locks, of which the following is a specification.

This invention relates to new and useful improvements in permutation door knob locks.

The primary object of the invention is to provide a permutation device upon the knob shank of a spring latch for doors and whereby both knobs of the door may be thrown out of operative engagement with the latch upon a predetermined positioning of the permutation members while upon returning the permutation members to their proper positions, the latch may be readily actuated for shifting the same in the door opening operation.

A further object of the device is to provide a knob spindle having one knob longitudinally shiftable thereon for operatively positioning a latch actuating member on either its operative or inoperative positions upon first setting a proper combination upon permutation members carried by the knob spindle.

A still further object is to provide a spring latch of substantially the usual construction, the same being secured to one side of the door and freely operable by a knob and having a shiftable knob upon the outer side of the door adapted to be moved and out of operative engagement with the latch upon properly setting permutation members journaled upon the spindle and adjacent one of the knobs.

With these general objects in view and others that will appear as the nature of the invention is better understood, the same consists in the novel combination and arrangement of parts hereinafter fully described, illustrated in the accompanying drawings and pointed out in the appended claims.

In the drawings forming a part of this application and in which like designating characters refer to corresponding parts throughout the several views:—Figure 1 is a large view of a door provided with the present invention and broken away upon the line of passage of the spindle therethrough, the outer door knob being shown in vertical

section, the elements being shown in their operative latch actuating positions. Fig. 2 is a similar view with the spindle rotated a quarter turn from that illustrated in Fig. 1 and showing the elements positioned incapable of actuating the latch. Fig. 3 is a plan view of the lock casing with a portion of the front wall removed and showing the latch in its normal projected position. Fig. 4 is a similar view but showing the latch as retracted. Fig. 5 is a central vertical longitudinal view of the device taken upon the axial line of the knob spindle, a portion of the door being shown in section and with the elements positioned as shown in Fig. 2. Fig. 6 is a similar view with the elements positioned as shown in Fig. 1. Fig. 7 is a vertical transverse sectional view taken upon line VII—VII of Fig. 5. Fig. 8 is a similar sectional view taken upon line VIII—VIII of Fig. 6. Fig. 9 is a perspective view of the spindle detached, and Fig. 10 is a perspective view of the latch actuator detached.

Referring more in detail to the drawings, it is designed to provide a door herein illustrated at 10 with a lock casing 11 of substantially the usual construction and positioned upon one side of the door and there provided with a turn knob 12 whereby the spring latch or catch 13 may be readily moved whenever desired from the interior of the room which is provided with the said door. The said latch 13 is slidably mounted within the casing 11 and is normally projected by means of a leaf spring 14 carried by the casing and engaging a shoulder 15 of the said latch. The usual turn yoke 16 is also provided within the casing with its hub 17 journaled through the opposite sides thereof and having its projecting ends 18 operatively engaging the lugs 19 of the latch. A knob 20 is provided upon the opposite side of the door and has a six sided socket or chamber 21 therein which slidably receives a correspondingly shaped shank 22 and whereby the outer knob is slidably mounted upon the said shank and rotatable therewith. A spindle 23 of a general cylindrical form is secured by means of a pin 24 within the central longitudinal bore 25 of the shank while the said spindle is journaled through an opening or perforation 26 of the door and then projects through the casing 11 and the square cen-

tral opening 27 of the yoke hub 17. The said spindle is freely rotatable within the said door perforation and casing and yoke opening upon being turned in either direction by means of the outer knob 20 while the unattached end of the spindle is squared as at 28 and is fitted into an open four sided longitudinal bore 29 of the inner knob shank 30 and whereby as will be evident any turning of either of the knobs will result in a similar actuation of the other knob.

The spindle 23 is provided with a longitudinal side slot 31 within which the latch actuator 32 is slidably mounted, one end portion of the said actuator as at 33 being square in cross section and adapted to be moved within the end portion 34 of the slot 31 which is in the spindle end portion 28. The opposite end of the actuator is reduced and is cylindrical in form and constitutes a rod extension 35 which is slidably positioned through a perforation 36 in an end cap 37 of the shank bore 25, while the free end of the rod is headed as at 38 or otherwise permanently secured to the outer shiftable knob 20. By this arrangement it will be seen that the actuator being slidable within the spindle slot 31 is freely revolvable within the hub opening 27, when the squared portion 33 of the actuator is positioned within the lock casing 11 and the yoke hub 17 thereon and as illustrated in Figs. 3 and 5 of the drawings. A projecting edge 39 is provided upon the actuator adjacent the square end 33 thereof and upon sliding the actuator toward the knob 12, the edge 39 is positioned within the yoke opening 27 and engages one of the corners 40 thereof, as best illustrated in Fig. 4 and also shown in Fig. 6 and in which position the spindle is engageably secured to the turn yoke so that any movement of either knob will actuate the said yoke for operating the latch. The edge 39 projects from the peripheral plane of the spindle to the same height as the rib 41 of the said actuator and which rib is in alinement with the edge 39. The rib 41 is cut away forming four spaced notches 42 upon the actuator, the bottom walls 43 of which notches substantially conform to the periphery of the spindle. Two permutation collars 44 are journaled upon the spindle between the door and the knob 20 and are freely rotatable thereon whenever the actuator is slidably positioned therethrough with any of its notches 42 so positioned as to receive the said collars therein. The said collars are journaled upon the said spindle as set forth by means of their central perforations 45 and are provided with notches 46 opening into the said perforations and whereby the rib 41 of the actuator may be slidably moved through the said collars when the notches

46 of each of the collars are brought into alinement with each other and with the said rib 41.

Rings 47 having similar perforations and notches as the collars 44 are interposed between the said collars and also between the collars and the door and shank and are rigidly mounted upon the spindle 23. By this arrangement it will be seen that with the elements positioned as illustrated in Figs. 1 and 6 and with the knob 20 pushed inwardly, the latch actuator will be in engagement with the yoke hub for the ready manipulation of the latch upon a turning of either knob. The collars 44 are at such a time preferably turned to any positions upon the outer two of the actuator notches 42 so that the actuator cannot be longitudinally shifted either accidentally or by an unauthorized person.

When desired to position the latch so that the knobs will be incapable of actuating the same, the permutation collars are turned so that the collar notches 46 are in alinement with the actuator rib 41 and then the knob 20 is pulled outwardly to the position shown in Figs. 2 and 5 and at which time the spindle and actuator will freely turn within the yoke opening 27 and without in any manner influencing the latch and in which position it will be evident that with the door closed and the latch in engagement with its keeper, it will be impossible to open the door. The collars 44 are provided with any desired permutation characters such as the figures 47 being here illustrated as setting up a combination of four and seven upon the two collars as illustrated in Fig. 2 in order to allow the shifting of the actuator by the knob 20.

It will thus be seen that a lock structure is provided in which the permutation members may be positioned upon either side of a door that may be desirable, the same being operable to permit one of the knobs to be shifted for bringing both of the knobs either in or out of operative connection with the normally projected latch.

While the forms of the invention herein shown and described are what are believed to be preferable embodiments thereof, it is nevertheless to be understood that minor changes may be made in the form, proportion and details of construction without departing from the spirit and scope of the invention as claimed.

What I claim as new is:—

1. In combination with a door having a latch casing and a normally projected latch mounted thereon, a spindle revolvably mounted through said door and casing and having a longitudinal slide slot therein, a shank secured to the outer end of said spindle, a knob having a socket therein slidably mounted upon said shank and revolvable

therewith, and a latch actuator slidably positioned within the said slot and rigidly secured at its outer end to the said knob.

2. The combination with a door having a normally projected latch mounted thereon, a turn yoke for said latch having an angular opening therethrough, a spindle extending through said door and said yoke opening and being freely revoluble, a shank secured to the outer projecting end of said spindle, a knob having a socket therein and slidably mounted upon said shank, a latch actuator slidably positioned upon said spindle and having its outer end secured to said knob and having a projecting edge adjacent its inner end portion adapted for engaging within the yoke opening when said knob is inwardly positioned upon the shank.

3. In combination with a latch having a turn yoke and a spindle freely revoluble through the said yoke, of a latch actuator slidably mounted upon the said spindle and provided with a plurality of side notches, permutation collars journaled upon said spindle and having inwardly opening notches and being freely revoluble only when in alinement with said actuator notches, the said actuator having a projecting rib adapted for slidable reception within the said collar notches when positioned in alinement therewith.

4. A device of the class described comprising a door having a perforation therethrough, a latch casing upon said door, a normally projected latch within said casing, a turn yoke for said latch having a rectangular opening therethrough, a spindle journaled through said door perforation and projecting through said yoke opening and casing, a knob secured to the projecting end

of the spindle, the said spindle having an open side slot therein substantially its entire length and terminating within the said squared end portion, a shank having angular outer faces rigidly secured to the opposite end of said spindle and having a central bore, a movable knob slidably mounted upon said shank, a latch actuator slidably positioned within said spindle slot and rigidly secured to said shiftable knob and having a projecting side edge slightly spaced from its opposite end and adapted for engagement with said yoke when positioned through the said opening thereof.

5. In combination with a latch, and an operating yoke therefor having a squared opening in the hub portion, a revolvably mounted knob spindle positioned in the squared opening of the yoke hub having a longitudinal side slot and one end of said spindle being rectangular in cross-section, a knob rigidly secured to said squared end of the spindle, a latch actuator slidably-mounted within said slot and having a squared end portion and a projecting side edge adjacent thereto, and a shiftable knob secured to the end of said actuator opposite to the squared end thereof adapted to shift said latch actuator to position the projecting side edge of said actuator into a corner of the squared opening of the yoke to lock the spindle and yoke together to shift the latch.

In testimony whereof I affix my signature in presence of two witnesses.

CLEMENT KATCHIR.
